(57) **CLAIM**

The ornamental design for a coordinate input device, as shown and described.

DESCRIPTION

FIG. 1 is a front top right isometric view of a coordinate input device according to my new design;

FIG. 2 is a rear top right isometric view of the coordinate input device of FIG. 1;

FIG. 3 is front view of the coordinate input device of FIG. 1;

FIG. 4 is a rear view of the coordinate input device of FIG. 1;

FIG. 5 is a top view of the coordinate input device of FIG. 1;

FIG. 6 is a bottom view of the coordinate input device of FIG. 1;

FIG. 7 is a left side view of the coordinate input device of FIG. 1;

FIG. 8 is a right side view of the coordinate input device of FIG. 1;

FIG. 9 is a rear view of the coordinate input device of FIG. 1, showing the device in a second position;

FIG. 10 is a top view of the coordinate input device of FIG. 1, showing the device in the second position;

FIG. 11 is a bottom view of the coordinate input device of FIG. 1, showing the device in the second position;

FIG. 12 is a left side view of the coordinate input device of FIG. 1, showing the device in the second position;

FIG. 13 is a right side view of the coordinate input device of FIG. 1, showing the device in the second position;

FIG. 14 is a rear view of the coordinate input device of FIG. 1, showing the device in a third position;

FIG. 15 is a top view of the coordinate input device of FIG. 1, showing the device in the third position;

FIG. 16 is a bottom view of the coordinate input device of FIG. 1, showing the device in the third position;

FIG. 17 is a left side view of the coordinate input device of FIG. 1, showing the device in the third position; and,

FIG. 18 is a right side view of the coordinate input device of FIG. 1, showing the device in the third position.

The broken lines show portions of the coordinate input device which form no part of the claimed design.
